ABSTRACT OF THE DISCLOSURE

In a transmit receive system comprising an electronic scanning antenna formed by a network of elementary sources and associated phase-shifters, the conventional T-R switch is replaced by the combination of at least one four arm balanced junction and π phase-shifting means.

The present invention relates to electronic scanning antennae formed by a network, having one or two dimensions of sources or elementary antennae. These sources are, for example, supplied from a single transmitter through a power distribution system. The feeder of each source contains a device for electronically controlling its phase.

A phase gradient may be thus established along the network, for adjusting the direction of the main radiation lobe of the antenna.

The technique for connecting the antenna alternately to the transmitter and to the receiver generally consists in using a nonreciprocal device, generally called "T-R switch" which carries out a switching either on the receipt of an external order, or automatically if the non reciprocity is obtained by using a difference in the characteristics of the transmission and reception waves. Generally, gas-filled tubes or ferrite or semiconductor devices are used.

In all cases the T-R switch is subjected to the action of the whole of the transmitted power, and this requires a complicated bulky and costly device which is very difficultly built.

It is an object of this invention to provide a novel device for connecting the sources of an electronic scanning antenna and effecting the transmission-reception switching without using any T-R switch.

According to the invention, there is provided a transmit-receive system comprising: transmitting means having a sync output and a signal output, receiving means having a signal input; aerial means comprising a first plurality of radiating sources and controllable phase-shifters, said plurality having a first terminal and a second plurality of radiating sources and controllable phase-shifters, said second plurality having a second terminal; programming means for controlling said phase shifters, having a first plurality of outputs coupled to said phase-shifters of said first plurality, and a second plurality of outputs coupled to said phase-shifters of said second plurality; and a coupling circuit for alternately coupling said signal output and said signal input to both said terminals, said circuit comprising a balanced hybrid junction having a first, a second, a third and a fourth arms respectively coupled to said signal output, to said first terminal, to said second terminal, and to said signal input, said first and fourth arms being non coupled to each other, and control means having a control input coupled to said sync output for phase-shifting by $\pm\pi$ the signals received at one of said terminals, said control means being coupled to said phase-shifters of said second plurality.

For a better understanding of the invention and to

show how the same may be carried into effect reference will be made to the accompanying drawings, in which:

FIG. 1 shows diagrammatically an electronic scanning antenna supplied in a conventional manner.

FIG. 2 shows diagrammatically an embodiment of an electronic scanning antenna supplied according to the invention.

FIG. 3 shows the operation of a balanced hybrid junction with four branches; and

FIG. 4 shows diagrammatically a "monopulse" radar antenna improved according to the invention and FIG. 5 shows in detail a portion of a circuit according to the invention.

The conventional electronic scanning antenna arrangement shown in FIG. 1 comprises sixteen elements S_1 to S_{16} and formed, for example, by dipoles having a length $\lambda/2$, where λ is the wavelength of the operating wave. Only a few of the elements are shown in the drawing.

The elements are generally associated with a reflector P .

The feed branch of each element contains in series a variable phase-shifter. Only two phase-shifters Ph_1 and Ph_{16} have their references on the drawing, for the sake of clarity.

The term "variable phase-shifter" is used here in the widest sense, that is to say, it covers any device such that a signal traversing the same undergoes a change in the phase as a function of a control signal applied to the control input of the phase-shifter. The control of each phase-shifter is represented symbolically by an arrow. The signal terminals of the phase-shifters which are not connected to the elements are connected to a conventional duplexer D through a device for distributing the power, comprising fifteen dividers d_1 to d_{15} , shown here in the form of T's, each of them distributing, for example in an even manner, the power applied to its input branch amongst its output branches.

The sixteen phase-shifters are controlled electronically at any moment so as to impart to the elementary elements the phase law, giving to the diagram of the antenna the desired direction of radiation. The transmitter E and the receiver R are connected in a conventional manner to the duplexer D .

The antenna according to the invention is shown in FIG. 2, wherein the elements identical to those of the conventional antenna of FIG. 1 are marked with the same references. The drawing shows again the transmitter E , the receiver R , the reflector P , the element S_1 to S_{16} , the phase-shifters Ph_1 to Ph_{16} and the dividers d_2 to d_{15} . Here, the transmitter and the receiver are connected to the uncoupled arms 1 and 4 of a magic tee T whose arms 3 and 2 are connected to the inputs of the dividers d_2 and d_3 . Moreover, the eight last outputs of the control device C of the phase-shifters (which has not been shown in FIG. 1 in order not to overload this drawing and which is of conventional construction), are here connected to the control inputs of the phase-shifters Ph_9 to Ph_{16} no longer directly, but through a device I with eight inputs and eight outputs which, according to whether it is in the inoperative or in the working position, transmits to the phase-shifters the orders issued by the control device C or orders derived therefrom, and causing an additional variation of the phase-shift by the amount π . The device I , which acts, when it is in the operative position, in some way, in the same manner as phase-shifters by $\pm\pi$ placed in series with the phase-shifters Ph_9 to Ph_{16} , is controlled, by the system transmission synchronization block, represented symbolically by the output SE of the transmitter E , in such a way that it is in inoperative position during the transmission and in operative position shortly afterwards. If φ_i ($i=1$ to 16) is the phase-shift introduced by

a phase-shifter Ph_i in the transmission and φ'_i that introduced by the same phase-shifter in the reception, it follows that $\varphi'_i = \varphi_i$ for $i \leq 8$ and $\varphi'_i = \varphi_i \pm \pi$ for $i \leq 9$.

The signals in the arms 2 and 3 which were in phase during the transmission when the branch 1 was fed by the transmitter, are now in phase opposition. Under these conditions, the whole energy received passes into the branch 4 which is connected to the receiver. This results from the very principle of operation of balanced hybrid junctions, such as the magic tee T in FIG. 2, which is discussed hereinafter with reference to FIG. 3. In this drawing, the junction T only is shown and the drawing indicates, without brackets, the values of the signals when the phases φ_2 and φ_1 at 2 and 3 are equal, and inside of brackets, the values of these signals when these phases differ by π . By using the conventional notations of electromagnetism, e being the base of Neperian logarithms and j the conventional symbol of imaginaries, the signals at 2 and 3 are, respectively, $a2 = Ae^{j\varphi_2}$ and $a3 = Ae^{j\varphi_1}$, A being the amplitude of the signals. If $\varphi_2 = \varphi_1$, the signal $a4$ in the arm 4 is zero and the signal $a1$ in the arm 1 is proportional to the sum of the signals $a2$ and $a3$, i.e., $a1 = K2Ae^{j\varphi_1} = K2Ae^{j\varphi_2}$, where K is a constant coefficient dependent on the type of junction used.

In 3 db hybrid junctions, which are the best known junctions,

$$K = \frac{1}{\sqrt{2}}$$

and $a1 = \sqrt{2}a$.

If $\varphi_2 = \varphi_1 \pm \pi$, $a1$ is zero and $a4 = \sqrt{2}A$.

During the transmission, only the branch 1 is fed, $a1$ is equal to $Ee^{j\varphi}$ and $a2 = a3 = E/\sqrt{2e^{j\varphi}}$, where E is the amplitude of the signal supplied by the transmitter.

During the reception, owing to the action of the device I, $\varphi_2 = \varphi_1 \pm \pi$ and the received energy is directed wholly to the arm 4 which is connected to the receiver.

Naturally, the same result may also be obtained by changing the phase-shift by π in the reception in the feed branches of the sources S_1 to S_8 and not changing the phases in the branches of the sources S_9 to S_{16} .

In this way, the duplexer has been eliminated in a simple manner at the price of replacing a simple power divider d_1 by a balanced divider T, for example by a magic tee; moreover, balanced dividers are often used in power distribution for other reasons.

Obviously, the invention is not limited to the embodiment hereinbefore described, relating to the case where the signals received by all sources are added, in which case only a single hybrid junction is required.

In certain cases, it is necessary to make the partial sums of signals received by certain groups of source. This is the case particularly with "monopulse" radar antennae.

FIG. 4 gives, by way of non limitative example, a diagram of an application of the antenna according to the invention to a monopulse antenna with electronic scanning in elevation and azimuth. In this case, nothing is changed during the transmission, but in the reception it is necessary to form partial sums of the signals received by each quarter of the element panel, that is to say, the sums of signals received by the sources S_1 to S_4 , S_5 to S_8 , S_9 to S_{12} , and S_{13} to S_{16} .

The dividers d_4 to d_7 will therefore be replaced by magic tees (or other hybrid junctions with balanced arms) T_1 to T_4 , having, respectively arms i_1 to i_4 , where $i=1$ to 4, wherein the arm i_m of a junction ($m=1$ to 4) has the same function as the arm m of the junction T in FIG. 2.

The junction T in FIG. 2 is therefore useless and a simple power divider, such as d_1 (FIG. 1) can be used. The arms 11 and 21 of T_1 and T_2 are connected to the divider d_3 and the arms 31 and 41 of T_3 and T_4 to the divider d_2 , whilst the arms 13, 12, 23, 22, 33, 32, 43 and

42 are connected, respectively, to the dividers d_8 , d_{10} , d_9 , d_{11} , d_{12} , d_{14} and d_{13} , d_{15} .

A device I', identical to the device I is now placed at the control inputs of the phase-shifters Ph_2 , Ph_4 , Ph_6 . . . etc, i.e., at inputs of phase-shifters with even indices. In this manner, the summation of the signals coming from the elements is no longer made in the branch of the T connected to the transmission, but in the fourth arm, that is to say, in 14, 24, 34 and 44.

10 Thus, by designating as b_i the signal received by the source S_i ($i=1$ to 16), it follows that there is:

at 14 a signal $B_1 = b_1 + b_2 + b_3 + b_4$

at 24 a signal $B_2 = b_5 + b_6 + b_7 + b_8$

at 34 a signal $B_3 = b_9 + b_{10} + b_{11} + b_{12}$

15 at 44 a signal $B_4 = b_{13} + b_{14} + b_{15} + b_{16}$

The signals B_1 to B_4 can be treated in sum and in difference as known per se in monopulse antennae.

To this end, the branches 14, 24, 34, 44 are connected 20 to the corresponding inputs of a monopulse receiver RM.

Various known means may be used in order to vary 20 by $\pm \pi$ the relative phase-shift introduced by phase-shifters Ph_9 to Ph_{16} (FIGURE 2) or Ph_2 , Ph_4 . . . Ph_{16} (FIGURE 4) between the transmission and the reception, the 25 choice of said means depending mainly on the type of the phase-shifters used.

Figure 5 represents a non limitative example of carrying out said π phase-shift in the case of Latching type phase-shifters Ph_i .

30 For the sake of clarity and in order to avoid overloading the figure, only one phase-shifter Ph_i and only the connections from devices C and I to the same are shown on FIGURE 5.

It is assumed here, by way of example, that phase-shifter Ph_i comprises four ferrite elements, which, when positive electrical pulses are applied, induce respective phase-shifts of 22.5° – 45° – 90° and 180° . These elements and their respective control circuits are symbolically shown at F_{i1} , F_{i2} , F_{i3} and F_{i4} .

35 In this case, the control device may be of the binary type, including for the control of each phase-shifter Ph_i , four output feeders f_{i1} , f_{i2} , f_{i3} and f_{i4} , respectively associated with elements F_{i1} , F_{i2} , F_{i3} and F_{i4} .

The part I_i of the device I associated with phase-shifter 40 Ph_i comprises four input terminals b_{i1} to b_{i4} , four output terminals b'_{i1} to b'_{i4} and a control terminal b_{i5} which is coupled to the control input of device I, i.e. to the output SE.

45 Terminals b_{i1} to b_{i4} are coupled to feeders f_{i1} to f_{i4} respectively and terminals b'_{i1} to b'_{i4} to elements F_{i1} to F_{i4} .

50 Terminals b'_{i1} to b'_{i3} are directly coupled to terminals b_{i1} to b_{i3} which are shown only for consistency with b_{i4} , while b'_{i1} to b'_{i3} could be coupled directly to feeders f_{i1} to f_{i3} .

55 Terminal b_{i4} is coupled to one of the two inputs of an anticoincidence circuit O_i , whose other input is coupled to SE, and whose output is coupled to terminal b'_{i4} .

Thus, the element F_{i4} is excited with an electrical pulse 60 when one of the inputs of circuit O_i is fed with a signal, and is not excited when the two inputs of the latter are simultaneously fed or unfed.

Two cases may happen:

(1) The phase-shift φ_i at the transmission time is 65 smaller than π : both inputs of circuit O_i are unfed when transmission is effected. At the reception time, only that input of circuit O_i which is coupled to SE is excited, thus $\varphi'_i = \varphi_i + \pi$;

(2) The phase-shift φ_i at the transmission is greater 70 than π : only that input of circuit O_i , which is coupled to terminal b_{i4} , is excited when transmission is effected and circuit F_{i4} is operated.

At the reception time, both inputs of circuit O_i are 75 excited, which results in non-operation of circuit F_{i4} , thus $\varphi'_i = \varphi_i - \pi$.

The required condition $\varphi'_i = \varphi_i \pm \pi$ has thus been met in both cases.

Naturally, the invention is not limited to the embodiments hereinbefore described and given merely by way of example.

The invention has been heretofore described in the simplest case, where the utilized balanced hybrid junctions are of the type in which applying a signal to arm 1 results in two in-phase signals in arms 2 and 3.

Of course, the invention may also be put into practice with junctions of a different type, where applying a signal to arm 1 results in two signals in arms 2 and 3, the relative phase-shift of which has a constant value φ_0 , different of zero. In this latter case, it will be necessary to compensate, for the phase-shift φ_0 , the phase-shift φ_1 introduced by those among the phase-shifters Ph_1 which are placed in circuits fed through arm 2.

It will be also noted that the invention is still usable each time an aerial system having at least two terminals employed, no matter whether or not it is a scanning system. In the case where the aerial feed system does not include phase-shifters per se, a device for phase-shifting by 180° will be alternately placed in the connecting circuit of one of the terminals.

Nevertheless, the invention is of particular interest when electronic scanning antennae are involved because phase-shifters are existing per se in the circuits of said antenna, each of said phase-shifters being traversed by only a portion of the total power.

Of course, the number of the elements of the network forming the antenna, and their grouping may be different from those described. The invention may be for example used with advantage in electronic scanning antennae of reduced dimension as described in the copending patent application filed by Sorge Landesman and Jacques Salmon, for "Steerable Antenna System," Ser. No. 598,146, filed November 28, 1966 and assigned to the same assignee.

What is claimed is:

1. A transmit-receive system comprising transmitting means having a sync output and a signal output, receiving means having a signal input; aerial means comprising a first plurality of radiating elements and controllable phase-shifters, said plurality having a first terminal and a second plurality of radiating elements and controllable phase-shifters, said second plurality having a second terminal; programming means for controlling said phase shifters having a first plurality of outputs coupled to said phase-shifters of said first plurality, and a second plurality of outputs coupled to said phase-shifters of said second plurality; and a coupling circuit for alternately coupling said signal output and said signal input to both said terminals, said circuit comprising a balanced hybrid junction having a first, a second, a third and a fourth arms respectively coupled to said signal output, to said first terminal, to said second terminal, and to said signal input, said first and fourth arms being noncoupled to each other, and control means having a control input coupled to said sync output for phase-shifting by $\pm\pi$ the signals received at one of said terminals, said control means having an output coupled to said phase-shifters of the corresponding plurality.

2. A transmit receive system according to claim 1, wherein said control means comprise n anticoincident circuits having respective first inputs coupled to said sync output and respective second inputs respectively coupled to said second plurality of outputs.

3. A transmit receive system according to claim 1 wherein said receiver comprises a second signal input, said aerial means comprises further third and fourth plurality of radiating elements and phase-shifters, having respective further third and fourth terminals, said programming means having further third and fourth plurality of outputs coupled respectively to said phase-shifters of said third and fourth plurality, and said coupling means further comprises: a second balanced hybrid junction having a fifth arm, a sixth arm coupled to said third terminal, a seventh arm coupled to said fourth terminal, an eighth arm coupled to said further input, and a first three terminal divider junction having an input coupled to said transmitting means signal output, and respective outputs respectively coupled to said first and fifth arms, said control means being further coupled to said phase-shifters of said fourth plurality.

4. A system according to claim 3, wherein said receiver comprises a third and a fourth signal inputs, said aerial means comprises further fifth, sixth, seventh and eighth pluralities of radiating elements and phase-shifters having respective terminals, said programming means having further fifth, sixth, seventh and eighth pluralities of outputs coupled respectively to said phase-shifters of said fifth to eighth pluralities, and wherein said coupling means further comprises: a third balanced hybrid junction having a ninth arm, a tenth arm coupled to said fifth terminal, an eleventh arm coupled to said sixth terminal and a twelfth arm coupled to said third signal input, a fourth balanced hybrid junction having a thirteenth arm, a fourteenth arm coupled to said seventh terminal, a fifteenth arm coupled to said eighth terminal, and a sixteenth arm coupled to said fourth signal input, a second three terminal divider junction having an input and respective outputs respectively coupled to said ninth and thirteenth arms, and a third three terminal divider junction having an input coupled to said transmitter and two outputs coupled to said inputs of said first and second divider junction, said control means being further coupled to said phase-shifters of said sixth and eighth pluralities.

5. In a transmit-receive system comprising transmitting means having a sync output and a signal output, receiving means having a signal input, and aerial means comprising at least a first and a second terminals, the level of the received energies at said terminals being equal: a coupling circuit for alternately coupling said signal output and said signal input to both said terminals, said circuit comprising at least one balanced hybrid junction having a first, a second, a third and a fourth arms respectively coupled to said signal output, to said first terminal, to said second terminal, and to said signal input, said first and fourth arms being non coupled to each other, and control means having a control input coupled to said sync output for phase-shifting by $\pm\pi$ the signals received at one of said terminals.
